UNITED STATES PATENT OFFICE.

WILLIAM R. TEMPLETON, OF ROSLINDALE, MASSACHUSETTS.

APPARATUS FOR CLEANSING AND STERILIZING TUMBLERS.

1,114,066.

Specification of Letters Patent.

Patented Oct. 20, 1914.

Application filed October 18, 1913. Serial No. 796,054.

To all whom it may concern:

Be it known that I, WILLIAM R. TEMPLETON, citizen of the United States, residing at Roslindale, county of Suffolk, State of Massachusetts, have invented an Improvement in Apparatus for Cleansing and Sterilizing Tumblers, of which the following description, in connection with the accompanying drawing, is a specification, like characters 10 on the drawing representing like parts.

This invention relates to apparatus for cleansing and sterilizing tumblers and the like.

At soda-water fountains, in bar rooms, and 15 the like it is necessary to provide means for cleansing glasses. The requirements of such apparatus are that it may be conveniently positioned, so as not to occupy much space, that it shall be quickly and easily operated 20 and that it shall not cause discomfort or annoyance or be otherwise objectionable. Tumbler washers as usually constructed are fashioned to receive only one tumbler at a time and are open at the top. Usually, also, 25 the tumbler is held in place by the hand while being washed, for these reasons the use of scalding water or steam in these devices is practically impossible. Not only would the heat be unbearable to the hand, 30 but the steam and vapor escaping into the room would be disagreeable and objectionable. The usual result in practice is that tumblers are merely rinsed in cold water and are not sterilized; the objection to such 35 practice in public drinking establishments is obvious.

The object of my invention is to provide 40 an inclosed washing and sterilizing device for tumblers suitable for use in public drinking establishments and adapted for the use of hot water or steam.

In accordance with my invention I provide 45 an inclosing case a removable tumbler support and means for spraying the tumblers when in position in the casing.

The novel features of my invention will be fully described in the following specification and accompanying drawings and particularly pointed out in the claims.

50 Referring to the drawings in which I have illustrated a preferred embodiment of my invention, Figure 1 is a central transverse section of a tumbler washing and sterilizing device constructed in accordance with 55 the principles of my invention, taken on the line 1—1 Fig. 2, Fig. 2 is a central longitudi-

dinal section taken on the line 2—2 Fig. 1, Fig. 3 is a front elevation of the casing showing the slidable door and means for operating this door, Fig. 4 is a sectional view 60 shown in detail of a nozzle and sprinkler head with a tumbler held in position there-between, Fig. 5 is a plan view of a sprinkler head, and Fig. 6 is a plan view of the tray.

Referring to the drawings in detail, the 65 device illustrated comprises an inclosing casing 1, oppositely disposed spraying devices consisting of spray-nozzles 2, and sprinkler heads 3, and a glass supporting tray 4. The casing is made substantially 70 fluid tight and is illustrated as constructed of sheet metal with a rigid head at each end. In the front head 1 provide an opening 5 and a vertically sliding door 6 for closing this opening. As a convenient means 75 for operating this door I provide a rack 7 secured to the door and operated by a pinion 8 engaging the rack and fast to a shaft 9 rotatable in the brackets 10 secured to the casing. An operating crank 11 is secured 80 to one end of this shaft. As a convenient means of holding the door in open position I secure a ratchet wheel 12 to the shaft 9 and provide a pawl 13 pivoted to the casing in position to engage the ratchet wheel. An 85 outlet 14 in the bottom of the casing is arranged to be connected to the waste pipe.

A fluid supply pipe 15 passes through and is secured in one side of the casing as indicated at 16, a valve 17 being provided to 90 control the supply of fluid.

The portion of the fluid supply pipe within the casing 1 is shaped to present one or more vertical rectangular portions 80, and the nozzles 2 and sprinkler heads 3 are secured to the upper and lower sides of the rectangular portions. In the embodiment 95 of the invention herein illustrated there are four such rectangular portions 80, each one of which carries a plurality of sprinkler 100 heads 3 and nozzles 2, and these vertical rectangular portions are connected together by pipe connections 81 which provide means for distributing the fluid to the various rectangular portions. The nozzles may be 105 of any construction which will direct a spray to the inside of the tumblers. I have illustrated a nozzle consisting of a cap 19 provided with a plurality of openings 20 screwed on to the connector 21. The sprinkler heads are preferably so constructed that 110 jets of water will be directed against the

bottom and outside of tumblers. As illustrated in Figs. 4 and 5 these heads each consist of a body member in the form of a casting 22 which is larger than the bottom 5 of the tumbler and a face-plate 23 provided with a plurality of outer holes 24 and a central hole 25. The outer holes preferably slant inwardly to direct their jets toward the sides of the tumbler. A plurality of lugs 10 26 formed in the casting are threaded to receive screws 27 which secure this face-plate in position. The casting is screw threaded at its upper end to provide means for readily connecting it to the T-coupler. 15 A tray 4 is provided as a convenient means for supporting the tumblers in position between the spraying devices, and is slidable in ways 28. These ways are secured to the vertical legs of the rectangular portions 80 20 so that the supply pipes themselves form the support for the tray. I have illustrated this tray as designed to receive a dozen tumblers and accordingly have illustrated a dozen nozzles and a dozen oppositely disposed 25 sprinkler heads. The tray is provided with openings 29 which when the tray is in position in the casing are disposed directly above the nozzles. Openings 30, arranged around the openings 29 facilitate 30 the escape of water. The tumblers are placed upside down upon the tray, one over each of the openings 29. The nozzles thus direct a spray of water or steam to the inside of the tumblers and the sprinkler heads 35 which are positioned above direct sprays of water or steam to the outside, thus simultaneously spraying the inside and outside. By this arrangement the tumblers are simultaneously washed inside and outside and 40 will not be cracked by the sudden application of hot water or steam. The door 6, in the casing is of sufficient size to permit the passage of the tray with the tumblers mounted thereon. As will be clear from 45 the above description I have provided a cleansing and sterilizing device which is suitable for use at soda-water fountains, in bar rooms, and the like for sterilizing a number of tumblers simultaneously.

The device is so designed that the air 50 of the room will not be filled with escaping steam and vapor and may be employed without giving rise to objections such as follow the use of ordinary open tumbler washers when hot water is applied thereto. 55

Having fully described my invention what I claim as new and desire to secure by Letters Patent is:—

1. In an apparatus for washing and sterilizing tumblers, the combination with a casing, of a plurality of vertically-disposed rectangular-shaped pipe portions situated within the casing and connected together, means to supply a washing and sterilizing fluid to said pipe portions, spraying devices 60 depending from the upper horizontal members of said rectangular portions, nozzles projecting upwardly from the lower horizontal members of said portions, a tray to support tumblers to be washed having openings through which the liquid from the nozzles is delivered into tumblers supported on the tray, and means carried by the vertical legs of the rectangular portions to removably sustain said tray. 70 75

2. In an apparatus for washing and sterilizing tumblers, the combination with a substantially fluid-tight inclosing casing having a door opening and a door for closing said opening, an inlet pipe leading into said 80 casing, a plurality of vertically-arranged rectangular pipe portions situated within the casing and extending transversely thereof, means connecting said rectangular pipe portions to each other and to the inlet pipe, 85 a tumbler-receiving tray slidably sustained by the vertical legs of said rectangular pipe portions, spraying devices secured to the upper horizontal sides of said rectangular pipe portions, and nozzles secured to the 90 lower horizontal sides thereof.

In testimony whereof, I have signed my name to this specification, in the presence of two subscribing witnesses.

WILLIAM R. TEMPLETON.
